UNITED STATES PATENT OFFICE.

SAMUEL B. SHELDON, OF DULUTH, MINNESOTA.

GAS-PRODUCER.

1,350,472.

Specification of Letters Patent. Patented Aug. 24, 1920.

Application filed June 11, 1918. Serial No. 239,361.

To all whom it may concern:

Be it known that I, SAMUEL B. SHELDON, a citizen of the United States, and resident of Duluth, in the county of St. Louis and State of Minnesota, have invented certain new and useful Improvements in Gas-Producers, of which the following is a specification.

This invention relates to gas producers.

One of the objects of this invention is to simplify and improve means for disturbing the fuel in the coking zone for maintaining the same in a uniformly porous and open condition.

Another object is to improve the fuel 15 poker and the means for actuating the same.

Another object is to provide a gas producer having coöperative parts arranged to meet all the requirements for successful operation.

20 These and other objects are accomplished by means of the arrangement disclosed by the accompanying sheets of drawings, in which

Figure 1 is a plan view of my gas producer.

Fig. 2 is a fragmentary vertical sectional view of the upper part of the same, and

Fig. 3 is a vertical sectional view of the fuel feed and distributing arrangement.

30 The various novel features of my invention will be apparent from the following description and drawings and will be particularly pointed out in the appended claims.

In view of the fact that my invention relates to mechanism mounted on the top of the gas producer, only the upper part of the gas producer is shown.

The main body portion 10 of the gas producer has at its upper end a channel portion 11 in which the vertical flange 12 of the rotating top 13 moves. The top and the parts mounted thereon are all actuated through suitable mechanism by an electric motor 14, the shaft of which is provided with the pinion 15, meshing with a gear 16 mounted on a shaft connected to suitable gearing within a gear housing 17. Extending outward from this housing is a shaft 17, carrying a pinion 18, which meshes with 40 and drives a relatively large gear 19, mounted upon a shaft 20 to the outer end of which is secured a traction wheel 21 bearing upon the stationary body portion 10 of the gas producer, whereby the 50 top of the gas producer is rotated. Secured

to the other end of the shaft 17' is an eccentric 22 (see Fig. 2) operatively connected to a yoke member 23 secured to a shaft 24 upon which a walking beam 25 is mounted. By means of this eccentric drive arrangement the opposite ends of the walking beam 25 are given a rising and falling movement. Secured to each end of the walking beam 25 is a ball socket 26 in which is movably mounted a ball 27, the latter of which may be in a single piece or in a plurality of pieces. Extending upwardly from the ball 27 is a tubular portion 28 and extending downwardly from the ball 27 is another tubular portion 29, there being an opening through the main part of the ball 27 registering with the opening in the tubular portions 28 and 29. Extending through these openings is a threaded portion on a shank 30 of the poker. The lower end of the poker is not shown, 75 but it will be understood that the poker performs the function of disturbing the fuel in the coking zone to maintain the same in a uniformly porous and open condition. The tubular portion 28 of the ball 27 abuts a nut 31 adjustably mounted upon the threaded portion of the poker shank 30, the latter of which is slidably movable within the ball 27. The ball and socket joint for the poker is the same at each end of the walking beam. In 80 this connection it will be noted that the poker to the left of the center of the walking beam, as shown in Fig. 2, is located farther from the center of the gas producer than is the poker shown at the right of the center 85 of the gas producer. By means of this arrangement the outer annular portion of the fuel bed is disturbed by the outer poker and the inner annular portion of the fuel bed is disturbed by the inner poker, all of the fuel, including that in the coking zone, being disturbed during one complete revolution of the top. 90

By means of the ball and socket joint connection between the walking beam 25 and the shanks of the pokers, the pokers are free to drag a certain amount as the top of the gas producer is rotated and at the same time the poker is free to move in a line coincident with or parallel to the vertical plane of 100 movement of the walking beam 25. As shown, the walking beam 25 is in central position. Let it be assumed, however, that the actuating shaft 17' is moving in a clockwise direction, as viewed in Fig. 2. Accord- 105

ingly, the one arm of the walking beam will be depressed and the other arm of the walking beam will be raised. In view of the fact that the connection between the walking beam and the poker is more clearly shown in connection with the outer poker at the left-hand side of Fig. 2, the action in connection therewith will be considered specifically.

- 5 **10** As the left arm of the beam 25 raises, the poker will be raised, due to the shoulder arrangement between the tubular portion 28 of the ball 27 and the nut 31. During the downward movement of the arm of the walking beam 25, the poker follows the beam but falls as a result of its own weight, and regardless of the extent of downward movement of the arm of the walking beam, the poker will extend into the fuel bed only an amount in accordance with its own weight. In actual operation, when the end of the arm of the walking beam is in its lowermost position, the nut 31 of the poker shank 30 may be out of engagement with the upper end of the tubular portion 28 of the ball 27. This is due to the fact that the fuel has offered resistance to the downward movement of the poker to the extent that the latter was not able of its own weight
- 15 **20** to follow the walking beam for its full throw. If, however, it is desired that the poker should be positively thrust down into the fuel bed for breaking the same down or for any other reason, the walking beam 25 and the shank 30 of each of the pokers may be positively connected by link or clevis means 33, parts of which may extend through openings 32 and 33 in the tubular member 28 and the nut 31, respectively.
- 25 **30** It will be understood that the top 13 of the gas producer revolves continuously and at a relatively slow rate. As a result thereof, during the up and down movement of the pokers while they are in the fuel bed, the bottom of each of the pokers is caused to lag a certain predetermined amount thereby pressing the portion of fuel being poked circumferentially in advance of the poker a slight amount. This action takes
- 35 **40** place throughout the whole revolution, thereby treating all parts of the coking zone of the fuel bed the same and rendering the same uniformly porous. It is to be understood that the oppositely acting pokers are raised above the fuel, then move vertically down into the fuel and while still in the fuel bed lag a given amount before they are raised out of the fuel as the top of the producer rotates. By adjusting the nuts 31 on
- 45 **50** the shank 30 of each of the pokers, the vertical movement of the latter into the coking zone may be varied.
- 55 The shank 30 of each of the pokers is hollow, whereby a cooling medium, such as water, may be supplied thereto through

a suitable supply connection 34 and from which the excess amount of cooling fluid may pass through an overflow connection 35. Secured to the lower tubular portion 29 of the ball 27 is a skirt 36 extending down into an annular channel member 37, secured to the top 13 of the gas producer, whereby a water seal is formed to prevent the escape of producer gas through the opening 38 through which the poker shank 30 extends.

60 Mounted on the top 13 of the gas producer is a fuel hopper 39 which receives its supply of fuel through a chute 40, the upper end of which is in register with the supply opening 41 of a coal bin 42. As shown, the outlet 41 is arranged concentrically with respect to the gas producer and the fuel hopper 39 arranged eccentrically with respect to the center of the gas producer, the chute 40 accordingly being arranged at an angle. It will be appreciated, however, that these parts may be arranged in accordance with requirements.

65 While I am claiming the coal feed and distributing arrangement in a co-pending application, I will describe in a general way in this application, the general arrangement of the parts.

70 The coal hopper 39 preferably is divided into two compartments 43 and 44, separated by a central wall 45. Mounted in each of said compartments 43 and 44 for reciprocation therein is a plunger 46 operatively connected to an arm 47 keyed to a shaft 48 to which is connected an arm 49, connected in turn to a rod 50, one end of which is connected to a shaft 51, through an eccentric 52, whereby each of the plungers 46 is reciprocated. It will be understood that each of the 75 plungers has its own reciprocating mechanism, the latter in each case being operatively connected to the shaft 51, to one end of which is secured a gear 53 which is driven by gear 19. Fuel from the hopper 39 flows 80 downwardly in front of the plungers 46, the fuel sloping off in front of the plungers at an angle of repose. The fuel in front of the oppositely actuated plungers 46 is pushed onto a distributor 54, which is eccentrically arranged with respect to the vertical center of the gas producer and which is rotated from the shaft 51 by a belt or chain 55 passing around a pulley 56 on said shaft 51, around intermediate guide pulleys 57 and 58 85 and around a pulley 59 mounted at the upper end of the distributor 54. This distributor 54 is hollow for the purpose of water cooling, the water being fed down through the distributor through a pipe 60 and overflowing at 90 61 to form a water seal in the annular channel members 62. The floor 63 of the hopper 39 is water cooled as is also the partition or wall 45 between the compartments 43 and 44.

95 The top 13 of the gas producer is cooled 100

by forcing water into a central chamber formed therein by an annular wall 64 having circumferentially arranged openings 65 through which the water may flow radially 5 outward over the upper surface of the top for cooling the latter. The excess amount of cooling water supplied in this way may overflow the sides of the gas producer.

There may be various modifications of my 10 invention, as herein particularly shown and described and it is my intention to cover all such modifications which do not involve a departure from the spirit and scope of the invention, as set forth in the following 15 claims.

I claim:

1. In a gas producer, the combination of a walking beam, and pokers mounted on opposite sides of the center thereof for disturbing the fuel in the coking zone. 20
2. In a gas producer, the combination of a walking beam mounted for rotation and having arms of different lengths, and pokers mounted thereon at different distances from 25 the center, having different paths of movement.
3. In a gas producer, the combination of a walking beam, and a poker having an up and down movement and connected to the walking beam by a ball and socket joint whereby 30 the poker may have freedom of movement in a plurality of directions.
4. In a gas producer, the combination of a walking beam, eccentric means for actuating 35 said walking beam, and a poker mounted on

said beam for disturbing the fuel in the coking zone.

5. In a gas producer, the combination of an actuating member, and a poker having an up and down movement and connected to the actuating member by a ball and socket joint whereby the poker may have freedom of movement in a plurality of directions. 40

6. In a gas producer, the combination of a walking beam, a poker connected thereto 45 whereby the poker is positively moved in one direction and moves in a different direction under the influence of its own weight, and means whereby the poker may be positively actuated in said different direction. 50

7. In a gas producer, the combination of a lifting member, and a poker slidably connected thereto whereby the latter in its downward movement follows the actuating member under the influence of its own 55 weight and continues until it is stopped by the resistance of the fuel bed or by the actuating member.

8. In a gas producer, the combination of a rotary top, a walking beam mounted thereon, and pokers connected to said walking beam whereby the pokers travel for disturbing fuel in a circular path. 60

Signed at Duluth, Minnesota, this 3rd day of June, 1918.
